PROCESS FOR TREATING HYDROCARBONS

Walter A. Schulze, Bartlesville, Okla., assignor to
 Phillips Petroleum Company, a corporation of
 Delaware

Application April 8, 1940, Serial No. 328,545

5 Claims. (Cl. 196—28)

The present invention relates to a process for the production of motor fuel from crude hydrocarbon oils.

It has specific application to the treatment of those fractions of crude petroleum oils adaptable to vapor-phase treatment with contact catalysts at elevated temperatures for the production of motor fuel with improved antiknock characteristics and a high response to lead-alkyl knock suppressors.

Previous investigation has shown that the octane number response of motor fuels to additions of tetraethyl lead is a variant factor and greatly affected by the sulfur content of said motor fuel. Improvement in the so-called lead response of gasoline has been obtained by the process of vapor-phase catalytic decomposition of the sulfur compounds, e. g. U. S. Patent 2,016,271 issued October 8, 1935 to Schulze and Buell. Such a process is applicable to the treatment of motor fuel from any source, but the results vary somewhat when said process is applied to cracked gasolines.

I have now found that greatly improved results may be obtained by a radical alteration of the processing steps used in the manufacture of the gasolines from the base stocks. This discovery involves several co-acting steps which may be briefly described as follows: (1) a crude oil is heated under pressure and flashed under such conditions that the temperature of the vapors leaving the tower is in the range of 600 to 800° F., the vaporizable constituents at said temperatures thus being separated from the non-vaporizable material; (2) the aforementioned vapors comprising hydrocarbons in the range of gasoline, naphthas and gas oils are then passed over a desulfurizing contact catalyst which decomposes a great proportion of the sulfur compounds into hydrogen sulfide without any substantial decomposition of the hydrocarbons; (3) the treated vapors are fractionated to remove the hydrogen sulfide and, if desired, the straight run gasoline fraction; and (4) the hydrogen sulfide-free naphtha and gas oil are treated in the vapor form over contact catalysts of the bauxite type at temperatures in the range of 800° to 1050° F. to convert the hydrocarbons boiling above the gasoline range into lower boiling components. Additional steps which may be included are the catalytic polymerization of the light unsaturated hydrocarbons, primarily propylene and butylenes, and of finally blending these various components of high anti-knock characteristics and low sulfur content into improved motor fuels. Due to the low sulfur con-

tent of the cracking stocks, the polymer gasoline, also, will be much lower in sulfur content than that normally produced in the refinery charging undesulfurized stocks.

Such an innovation as the series of steps outlined above is particularly advantageous because it has been found that the sulfur compounds involved are less refractory in the naphthas and gas oils prior to cracking, and hence are removed to a greater extent than they would be from the cracked distillates. Also, with proper control of desulfurizing conditions, catalyst poisoning may be greatly reduced and longer operating cycles obtained by treating the total vaporizable material described above.

Several processes are known for the desulfurization of heavy residual oils, asphalts, tars and coal pastes but such processes involve high pressure hydrogenation and are too expensive for application to the treatment of potential motor fuel stocks. My discovery, however, that heavy naphthas and gas oil fractions may be treated in the vapor form at low pressures and without the addition of hydrogen gas greatly simplifies the processing of these potential motor fuel stocks and makes it possible to obtain much improved results in the subsequent catalytic cracking operations.

An important object of the present invention is to provide a unitary process for producing an improved motor fuel from crude oil containing sulfur.

An additional object of the present invention is to provide a process for economically producing a motor fuel with improved anti-knock characteristics and a high response to knock suppressors.

As stated previously, I have found that the maximum reduction in the sulfur content and maximum improvement in the lead response of the finished motor fuel (which in this instance is considered as a blend of the various streams produced from the crude oil) may be obtained by heating the crude petroleum oil under pressure to temperatures within the range desired for catalytic vapor-phase desulfurization, releasing the pressure on the heated oil to allow all the material vaporizable at said temperatures to separate from the non-vaporizable material, and passing the vapors without substantial condensation over a contact catalyst capable of effecting decomposition of the organic sulfur compounds. By operating in this manner any step-wise fractionation or separation of liquid components of said vapor is avoided with resultant savings in processing costs. Further, operation in this manner makes it possible to obtain good results in

desulfurizing the heavier fractions such as gas oil, since said fractions because of high boiling point and large content of asphaltic and/or waxy bodies are not adaptable to treatment in the absence of the light, lower-boiling components.

Passage of the vapors of a crude petroleum oil at suitable flow rates of 1 to 10 liquid volumes per hour per volume of catalyst over a contact catalyst at temperatures between 600° and 800° F. and at pressures between zero and 100 pounds per square inch results in the decomposition of a substantial proportion of the organic sulfur compounds into hydrogen sulfide without any substantial decomposition of the hydrocarbon constituents. Due to the absence of unsaturated hydrocarbons, there is no tendency for the hydrogen sulfide to be converted to refractory cyclic sulfur compounds, such as are formed in cracking operations on undesulfurized stocks. Likewise, absence of unsaturated hydrocarbons favors the decomposition of the sulfur compounds, the reaction being reversible in the presence of olefins. The hydrogen sulfide formed in my process must be removed at this point before proceeding with steps for the manufacture and/or separation of motor fuel. This removal of hydrogen sulfide may be done by chemical means or by fractionation, and the latter method is preferable since the desulfurized vapors must be fractionated prior to subsequent steps of the present invention.

Fractionation of the desulfurized vapors is carried out in a suitable unit by taking the normally gaseous hydrocarbons and the straight run gasoline overhead along with the hydrogen sulfide, and thus separating the hydrocarbon liquids boiling within the range of the desired straight run gasoline from the heavier kerosene, naphtha and gas-oil fractions. From this overhead fraction there is obtained a straight run gasoline of very low sulfur content and exceedingly high response to tetraethyl lead. This gasoline, after stabilization to remove the normally gaseous hydrocarbons and hydrogen sulfide, is of great value in blending with stocks to make leaded motor fuels on account of its great lead susceptibility.

The gaseous hydrocarbons from the above-described stabilization may be passed to a vapor recovery plant for the extraction of C₃ and C₄ hydrocarbons useful in production of motor fuels by means of thermal polymerization and the like. The heavy naphtha and gas-oil of greatly reduced sulfur content is available for thermal or catalytic cracking to produce high octane cracked gasoline of low sulfur content. If thermal cracking is employed, the resulting cracked gasoline will have a much lower sulfur content and a higher lead response that would be obtainable by desulfurization of said cracked fuel subsequent to the cracking operation.

The fourth step of the present invention contemplates the catalytic conversion of the desulfurized cracking stock over catalysts capable of supporting cracking or splitting reactions as an integral part of the process. The benefits of the initial desulfurizing step are thereby reflected not only in a motor fuel of lower sulfur content which needs no further desulfurizing treatment except the removal of H₂S but also in longer active periods for the cracking catalyst.

The catalytic cracking step is carried out by heating the cracking stock to a temperature in the range of 800° to 1050° F. and passing the vapors over an adsorbent mineral ore catalyst of the bauxite type said catalyst being herein-after referred to as a bauxite catalyst. Pres-

sures in the process may range from zero to about 300 pounds, while the flow rate may be about 0.2 to 3 liquid volumes per hour per volume of catalyst. In such an operation the conversion temperature will depend on the percentage of lower-boiling constituents which is left in the cracking stock after the separation of straight run gasoline. Thus it is possible to operate with substantially all of the gasoline content of the desulfurized oil being charged to the cracking unit, in which case cracking temperatures may be at the higher part of the indicated range. This is possible because of the diluent effect of the light gasoline which prevents over-conversion of the heavy ends.

However, because of the excellent lead response and the high blending value of the low-sulfur straight run gasoline, it is preferred to separate naturally occurring gasoline almost completely from the desulfurized stock charged to the cracking unit. In this case, conversion temperatures are regulated to prevent over-conversion and coking, with a second catalytic or thermal cracking treatment being performed on unconverted cracking stock if desired after separation of conversion products from the initial cracking operation. The adjustment of operating temperatures and contact time to suit the feed stock thus is a matter of choice within the scope of this invention.

The stream of vapors leaving the cracking catalyst may be cooled and passed to a fractionator wherein the gasoline vapors and the normally gaseous hydrocarbons are taken off overhead along with any hydrogen sulfide resulting from the action of the cracking catalyst while the unconverted constituents of the cracking feed stock are withdrawn as bottoms from the fractionator. This unconverted material may then be passed over a second cracking catalyst for further conversion to motor fuel. The overhead vapors from the first fractionator following the cracking unit may then be fractionated to separate normally gaseous hydrocarbons and to produce an end-point high octane cracked motor fuel which requires no further treatment except possibly clay treating.

The light gases separated from the effluent stream from the cracking unit may be freed of hydrogen sulfide, compressed and passed to a vapor absorption unit for separation into a lighter fraction containing substantial amounts of hydrogen gas and a heavier fraction containing C₃ and C₄ hydrocarbons, including substantial amounts of unsaturated C₃ and C₄ hydrocarbons.

Said heavier fraction, or the C₃ and C₄ portion of it, is well suited to passage over a catalyst for production of catalytic polymer gasoline which after fractionation may be blended with the cracked gasoline. The lighter fraction containing hydrogen and methane may, if desired, be returned to the stream of cracking stock, and used as a diluent gas or source of endothermal heat in the cracking operation.

To illustrate one embodiment of this invention, the following example is included. Such an example, however, must not be construed as limiting the invention since other modifications within the scope of this invention will be apparent to those skilled in the art.

Example I

A Texas Panhandle crude oil was heated in a pipe still to a temperature of 800° F. and allowed to flash in a separator wherein the total vapor-

izable material was removed from the residual oil at an average vapor temperature of 750° F. The total vapor thus resulting was passed through a bed of bauxite catalyst at substantially said vapor temperature and a pressure of 20 pounds gauge, the flow rate of vapors being maintained at a value equivalent to about 10 barrels of liquid oil per hour per ton of catalyst. The treated vapors were then passed to a fractionating unit for separation of hydrogen sulfide, normally gaseous hydrocarbons and straight run gasoline with about 360° F. end point. The remaining desulfurized cracking stock was then charged to a heater where the stream was vaporized and the vapors heated to a temperature of 950° F. The heated vapors were passed then to a chamber wherein an absorbent mineral ore cracking catalyst was maintained at substantially 950° F. and about 30 pounds pressure. The vapors from the catalytic cracking unit were then cooled and passed to a fractionator where the gasoline hydrocarbons and lighter gases were taken off along with a small amount of hydrogen sulfide resulting from a further decomposition of organic sulfur compounds by the cracking catalyst.

The unconverted cracking stock remained as a residual oil which was then passed to a second catalytic converter for further cracking. The vapors taken overhead from the primary fractionator were cooled and passed to a second fractionator where gaseous hydrocarbons were separated from the gasoline. The gaseous hydrocarbons separated from the cracked gasoline were passed to an absorption unit wherein hydrogen and lighter gases were separated from C₃ and C₄ hydrocarbons. Said C₃ and C₄ hydrocarbons containing a large percentage of unsaturates were then passed to a catalytic polymerization unit, and the effluent from said unit after fractionation produced an additional amount of gasoline of very high blending octane number.

The following comparative results illustrate the superior results obtained by this embodiment of the present invention as compared to the conventional refining of the same crude oil to produce successively straight run cracked and polymer gasoline from the undesulfurized total fraction vaporizable at 800° F.

	Old process	New process

The figure illustrates schematically one embodiment of the process comprising the present invention. According to this drawing, the crude petroleum oil is flash distilled in distillation unit 10 from which the mixture of vapor and liquid pass to a separator 11. From the separator the

vaporizable material passes without any substantial cooling to a catalyst chamber 12 for desulfurization. The treated vapors then pass to fractionating unit 13 wherein straight run gasoline and gaseous hydrocarbons along with hydrogen sulfide formed in 12 are taken overhead. The overhead vapors are cooled and fractionated in fractionator 14, from which the C₄ and lighter hydrocarbons and hydrogen sulfide are taken overhead and separated from the end-point, low sulfur straight run gasoline. The overhead gas may then pass to a compressor 15 and a fractionator 16 in which hydrogen sulfide is removed by fractionation, along with part of the C₃ hydrocarbons. The residual C₃ and C₄ hydrocarbons from this operation are useful in the manufacture of gasoline by thermal polymerization. If desired, the C₃ hydrocarbons may be largely retained by using chemical means for the removal of hydrogen sulfide prior to the gas fractionation step. The residual desulfurized liquid from 13 then passes to a heater 20 and thence to a catalyst chamber 21 for conversion of the heavy hydrocarbons to gasoline. The cracked vapors from 21 pass to a fractionator 22 where gasoline and gaseous hydrocarbons are removed along with any decomposed impurities from unconverted cracking stock. The gasoline and gaseous hydrocarbons are fractionated in unit 23 to separate C₄ and lighter hydrocarbons from the cracked gasoline. The gaseous hydrocarbons from 23 then may pass to a hydrogen sulfide removal unit 24, a compressor 25, and than to a vapor absorption unit 26, where C₃ and C₄ hydrocarbons are removed, and sent to a catalytic polymerization unit 27 for conversion of unsaturates to polymer gasoline. The effluent from 27 is then separated by fractionation in unit 28 to remove the unconverted C₃ and C₄ hydrocarbons which may then pass to thermal poly feed. The hydrogen and lighter hydrocarbons from 26 may be recycled if desired by alternate arrangement to the stream of cracking stock ahead of heater 20 to act as a diluent and source of endothermal heat to the cracking operation.

While the example and the drawing provide specific illustrations for the process of this invention, other modifications will become apparent in the light of the foregoing disclosure, and limitations are applied only according to the appended claims.

I claim:

1. The process for producing motor fuel from crude petroleum oil which comprises flash distilling said oil at a temperature between 600° and 800° F., separating the total material vaporizable at said temperatures from residual oil, passing said total vaporizable material at vapor temperature without substantial cooling at pressures between atmospheric and 100 pounds per square inch and flow rates between 1 and 10 liquid volumes of raw stock per hour per volume of catalyst, over a bauxite catalyst whereby a substantial proportion of the organic sulfur impurities is decomposed to hydrogen sulfide, fractionating the desulfurized material to separate normally gaseous hydrocarbons, hydrogen sulfide and a straight run gasoline, stabilizing the straight run gasoline to remove gaseous hydrocarbons and produce an end-point gasoline of low sulfur content and high lead response; heating the heavier fractions of said desulfurized material substantially denuded of gasoline and passing same over a bauxite catalyst at temperatures between 800° and 1050° F. and pressures between atmospheric

and 300 pounds per square inch to partially convert said heavy fractions by cracking into gasoline hydrocarbons, fractionating the vapors from the cracking catalyst to remove normally gaseous hydrocarbons and hydrocarbon vapors comprising a high octane cracked gasoline from unconverted heavy hydrocarbons, then separating the normally gaseous hydrocarbons by subsequent fractionation from the gasoline hydrocarbons, separating the gaseous hydrocarbons into a lighter and a heavier fraction, and passing said heavier gaseous fraction containing substantial amounts of olefins over a catalyst for the production of polymer gasoline, fractionating the effluent from the catalytic polymerization operation to obtain thereby additional high octane gasoline and combining said low sulfur, high lead-response straight run gasoline with said high-octane cracked and polymer gasoline to obtain superior yield of a valuable motor fuel.

2. The process for producing motor fuel from crude petroleum oil which comprises flash distilling said oil at a temperature between 600° and 800° F., separating the total material vaporizable at said temperatures from residual oil, passing said total vaporizable material without substantial cooling over a bauxite catalyst at pressures between atmospheric and 100 pounds per square inch, and flow rates between 1 and 10 liquid volumes of feed stock per hour per volume of catalyst, whereby a substantial proportion of the organic sulfur impurities is decomposed to hydrogen sulfide, fractionating the desulfurized material to separate a straight run gasoline, stabilizing said straight run gasoline to remove normally gaseous hydrocarbons and hydrogen sulfide and produce an end-point gasoline of low sulfur content and high lead response; heating the heavy fraction of said desulfurized material substantially denuded of gasoline and passing same over a bauxite catalyst at temperatures between 800° and 1050° F. and pressures between atmospheric and 300 pounds per square inch to partially convert said heavy fraction by cracking into gasoline hydrocarbons, fractionating the vapors from the cracking catalyst to remove vapors comprising a high octane cracked gasoline from unconverted heavy hydrocarbons, condensing and stabilizing said cracked gasoline and combining same with the low-sulfur straight run gasoline to obtain a superior yield of a low sulfur, high lead response motor fuel.

3. The process for producing motor fuel from crude petroleum oil which comprises flash distilling said oil at a temperature between 600° and 800° F., separating the total material vaporizable at said temperatures from residual oil, passing said total vaporizable material at vapor temperature without substantial cooling over a solid adsorbent bauxite catalyst at pressures between atmospheric and 100 pounds per square inch and flow rates between 1 and 10 liquid volumes of feed stock per hour per volume of catalyst whereby a substantial proportion of the organic sulfur impurities are decomposed into hydrogen sulfide, fractionating the desulfurized material to segregate an end-point low sulfur straight run gasoline free of hydrogen sulfide and a low sulfur cracking stock, heating said cracking stock and

subjecting the vapors to cracking conditions to partially convert the heavy hydrocarbons into gasoline hydrocarbons, fractionating the vapors from the cracking operation to obtain a high octane low sulfur cracked gasoline and blending said cracked gasoline with said straight run gasoline to produce a superior motor fuel.

4. The process for producing motor fuel from crude petroleum oil which comprises flash distilling said oil at a temperature between 600° and 800° F., separating the total material vaporizable at said temperatures from residual oil, passing said total vaporizable material without substantial cooling over a bauxite catalyst at pressures between atmospheric and 100 pounds per square inch, and flow rates between 1 and 10 liquid volumes of feed stock per hour per volume of catalyst, whereby a substantial proportion of the organic sulfur impurities is decomposed to hydrogen sulfide, cooling and fractionating the desulfurized material to remove light gases and a straight run gasoline with an end-point of 300° F., heating the residual fraction of said desulfurized material and passing same over a bauxite catalyst at a temperature between 950° and 1050° F., and pressures between atmospheric and 100 pounds per square inch to partially convert said residual fraction into gasoline, cooling and fractionating the vapors from the cracking catalyst to remove vapors comprising a high octane cracked gasoline and a light gas fraction high in hydrogen from unconverted heavy hydrocarbons, stabilizing said cracked gasoline to remove said light gas fraction, passing said light gas fraction to a vapor recovery system to separate C₃ and C₄ hydrocarbons from the lighter gases containing principally methane and hydrogen, recycling a portion of the methane-hydrogen mixture with the cracking stock ahead of the heater to supply endothermal heat to the cracking catalyst, and finally combining said high octane cracked gasoline with said low sulfur straight run gasoline to produce a superior motor fuel.

5. The process for producing motor fuel from crude petroleum comprising passing the crude oil to a heating zone and thence to a flashing zone to separate the vaporized and unvaporized material, the heat supplied to the heating zone being such that the temperature of the vaporized material is between 600 and 800° F., passing the vaporized material without cooling from the flashing zone into contact with a solid adsorbent bauxite catalyst at a pressure between atmospheric and 100 pounds per square inch and a flow rate between one and ten liquid volumes of feed stock per hour per volume of catalyst whereby a substantial proportion of the organic sulfur impurities are decomposed into hydrogen sulfide to yield a desulfurized stock, removing the hydrogen sulfide from the desulfurized stock, and passing desulfurized stock in contact with a bauxite catalyst at a temperature between 800 and 1050° F. and a pressure between atmospheric and 300 pounds per square inch to partially convert the desulfurized stock into gasoline containing a minimum of refractory cyclic sulfur compounds.

WALTER A. SCHULZE.
